GALVANIC ANODE ASSEMBLY

Harold A. Robinson, Midland, Mich., assignor to
The Dow Chemical Company, Midland, Mich.,
a corporation of Delaware

Application January 26, 1949, Serial No. 72,877

3 Claims. (Cl. 204—197)

1

This invention relates to an improved galvanic anode assembly for use in the cathodic protection of metal vessels.

In one form of cathodic protection of metal vessels against corrosion by natural waters, a consumable anode of galvanically active metal anodic to the vessel is suspended in the water and connected electrically to the vessel wall. The resulting flow of current maintains the vessel cathodic to the medium and minimizes its corrosion. A difficulty arises, however, in the protection of water heaters and water softeners operating on highly mineralized waters of low electrical resistance. In such waters, the anode develops more current than is needed, shortening its useful life unnecessarily, producing objectionable gassing, and occasionally imparting an undesirable color or odor to the water.

This excessive current flow may be prevented by inserting a resistor of suitable value in the circuit between the anode and the metal vessel. Such a resistor is usually housed in a special adapter fitting which also holds the anode in position and connects it electrically to the vessel. Prior adapters have, however, been expensive and poorly suited to quantity production, particularly with respect to the way in which the resistor had to be installed. They were further disadvantageous in that they provided no means for removing the built-in resistance from the circuit without destroying the whole adapter assembly, no matter how desirable such removal may have become due to changes in operating conditions.

It is therefore a principal object of the present invention to provide an improved resistor-type anode and adapter assembly which may be inexpensively produced and in which the resistor is easily installed. Another object is to provide an adapter assembly in which there is adjustable means for optionally shorting-out the resistor whenever circumstances demand.

These objects are attained in the invention by the use of a metal plug adapter having a recess in its base and a body of galvanically active metal one end of which is held by the plug and fits into it to a depth insufficient to rest on the end of the recess, the active metal being insulated electrically from the plug. A cartridge resistor and an electrically conducting compressible elastic member, such as a metal spring, are connected electrically in series and placed within the plug recess in such position between the end of the recess and the end of the galvanic body that the elastic member rests against one of the two ends and presses the resistor against the other of the

2

ends. The assembly may also include an adjustable screw or other means operable through the head of the plug for shortening out the cartridge resistor.

5 The invention may be explained in detail with reference to the accompanying drawings in which

Fig. 1 is a vertical section through an adapter assembly according to the invention;

Fig. 2 is a fragmentary cutaway view of a water tank with the assembly of Fig. 1 installed to protect the tank against corrosion;

Fig. 3 is a vertical section through an alternative form of assembly according to the invention;

Fig. 4 is a vertical section through another 10 form of assembly according to the invention; and

Fig. 5 is an enlarged detail of the screw, spring, and cartridge resistor in Fig. 4.

In Fig. 1, the adapter comprises a hexagonal-head brass or other metal plug 6 provided with 20 external pipe threads 7 and having a cylindrical axial recess 8 bored in its base. Integral with the plug is an extension 9 in the form of a cylindrical tube coaxial with the recess 8, the walls of the tube being sufficiently thin to be deformable 25 for crimping. Within the recess, and of substantially smaller diameter, is a tubular spacer 10 of wood or other electrical insulating material.

A galvanic anode in the form of a cylindrical magnesium rod 11 provided with a steel wire core 30 12 fits into the extension 9 to seat against the spacer 10. As shown, the rod 11 is reduced in diameter at its upper end in order to enter the extension 9 loosely. A sleeve of waterproof flexible electrical insulating material 13, such as a 35 rubber tube, is slipped over the end of the rod 11 so as to be interposed between the latter and the extension 9. The metal of the extension is crimped against the sleeve 13, providing a watertight joint and holding the rod 11 firmly in the 40 assembly.

Within the plug recess inside the spacer 10 are a cartridge resistor 14 and a steel or other electrically conducting spring 15. The resistor and spring are electrically in series, with the 45 spring resting against the end of the anode rod 11 in firm contact with it and pressing the resistor against the end of the recess 8 in electrical contact with the plug. Consequently, in the assembly illustrated, the galvanic anode 11 is held by the plug 6 but is connected electrically to it only through the resistor 14.

For use in domestic hot water tanks, the plug 6 is usually of a size to fit a $\frac{3}{4}$ " or 1" I. P. S. 55 tank opening, the anode is a 0.8 to 1.3-inch

magnesium-alloy rod 3 to 4 feet long, and the resistor is in the range of 5 to 20 ohms.

In Fig. 2, the assembly of Fig. 1 is shown in use in the cathodic protection of galvanized steel domestic water heater tank 16 having the usual inlet dip-pipe 17 and an outlet opening 18. The assembly is best installed through an auxiliary threaded opening 19 in the top of the tank. The plug 6 is screwed firmly into the opening so that the anode rod 11 is held suspended in the tank.

Fig. 3 is illustrative of an alternative form of the assembly of Fig. 1 in which the tubular spacer is omitted. The plug recess 8 is provided with a smaller central recess or socket 20 to receive the cartridge resistor 14. One end of a spring 21 is soldered to an end of the resistor, while the other end of the spring fits into a small socket 22 bored in the end of the core 12 of the rod 11.

The adapter assembly of Figs. 4 and 5 is similar to that of Fig. 1, but includes means for optionally shorting out the resistance between the anode and the plug. As shown particularly in Fig. 5, the cartridge resistor indicated generally as 23 comprises a ceramic or other insulating tube 24 around which is wound an electric resistance wire 25, the wire being covered with a coating of insulating cement 26. At the bottom or anode end the cartridge terminates in a metal cap 27 having a sharp point which bears against the core wire 12 of the anode 11. At the upper or plug end the cartridge is provided with an outside metal band 28. The resistance wire 25 is connected electrically and mechanically to both the cap 27 and the band 28 so that the latter constitute electrically isolated end elements which are connected through a resistor. Inside the ceramic tube 24 of the cartridge is a brass or other electrically conducting pin 29 which is soldered to the cap 27 but is insulated from the band 28. A steel coil spring 30 is soldered to the band 28, being thus in series with the resistor. The other end of the spring seats on a brass screw 31 provided with a sharp conical point as shown. This screw extends through a threaded hole 32 in the head of the plug 6 which is coaxial with the resistor 23.

When the screw 31 is adjusted so that its point does not touch the resistor core 29, the spring 30 presses the resistor against the end of the anode 11. Under these conditions, the anode 11 and plug 6 are connected only through the resistance element 25. However, when the screw 31 is tightened to bear against the brass core 29, the plug 6 and anode 11 are directly connected through the core, the resistance element being shorted out. In this construction it is thus possible to eliminate the resistance, or include it in circuit, as often as may be desired, simply by turning the screw 31, without having to remove the assembly from service.

While the assembly of the invention is usually employed in the cathodic protection of ferrous metal structures, it may be used in the protection of any corrodible metal, provided only that the rod 11 is formed of galvanically active metal anodic to the metal to be protected. The anodic metal is usually zinc, aluminum, magnesium, or a magnesium-base alloy, the latter two being comprehended by the term "magnesium" metal as used herein.

What is claimed is:

1. In a galvanic anode assembly for insertion through the wall of a metal vessel to be protected cathodically and comprising a metal plug having a recess in the base thereof, a body of galvanically active metal one end of which fits into the plug to a depth insufficient to rest on the end of the recess, and electrical insulation interposed between the plug and the metal body, the combination of a cartridge resistor within the plug recess, one end of which is connected electrically to the plug and the other to the metal body, and adjustable means mounted on and operable through the head of the plug for optionally shorting out the resistor.
2. In a galvanic anode assembly for insertion through the wall of a metal vessel to be protected cathodically and comprising a metal plug having a recess in the base thereof, a body of galvanically active metal one end of which fits into the plug to a depth insufficient to rest on the end of the recess, and electrical insulation interposed between the plug and the metal body, the combination of a cartridge resistor within the plug recess, one end of which is connected electrically to the plug and the other to the metal body, and an adjustable metal screw extending through the plug in electrical contact therewith in position optionally to short out the resistor.
3. In a galvanic anode assembly for insertion through the wall of a metal vessel to be protected cathodically and comprising a metal plug having a recess in the base thereof, a body of galvanically active metal one end of which fits into the plug to a depth insufficient to rest on the end of the recess, and electrical insulation interposed between the plug and the metal body, the combination of an electrically conducting spring and an elongated cartridge resistor within the plug recess, the cartridge comprising separate conductive end elements interconnected electrically through a resistor and a conductive core extending axially through the cartridge and connected electrically to only one of the end elements, the spring having one end in electrical contact with the end of the recess and the other end bearing against the end element of the cartridge which is not connected to the core to press the other end of the cartridge against the body of galvanic metal, and an adjustable screw extending through the head of the metal plug in electrical contact therewith and in position optionally to contact the core of the cartridge resistor.
